By his Atty. J. Dennis Jr.

United States Patent Office.

WILLIAM KENNEDY, OF NEW LONDON, PENNSYLVANIA.

Letters Patent No. 80,186, dated July 21, 1868.

IMPROVEMENT IN WATER-WHEELS.

The Schedule referred to in these Letters Patent and making part of the same.

TO ALL WHOM IT MAY CONCERN:

Be it known that I, WILLIAM KENNEDY, of New London, Chester county, State of Pennsylvania, have invented certain new and useful Improvements in Water-Wheels; and I do hereby declare the following description and accompanying drawings are sufficient to enable any person skilled in the art or science to which it most nearly appertains to make and use my said invention or improvements without further invention or experiment.

The nature of my invention and improvements consists in constructing a horizontal water-wheel with two rims or drums for buckets on the same axis, one mainly above the other, and the upper one being curved inward towards the axis, from the top downward, so as to contract its diameter at the bottom, and make it considerably less than the top diameter of the lower drum, in order that the water from both sets of buckets may be discharged downward; that from the set on the upper drum passing down between the upper and lower drums, and that from the lower set passing down between the lower drum and the surrounding case of the wheel.

In describing my improvements, I refer to the accompanying drawings, forming part of this specification—

Figure 1 being a plan or top view of the case of the wheel, with one-half of the cover left off to show the position of the gates in the water-passages, and

Figure 2 an elevation of the wheel, the right-hand half being a section through the centre, to show the relative position of the two rims or drums.

A is the central shaft of the wheel, which may turn in a step at the bottom, and be held in position by a journal in a brace or beam at the top, or in any of the methods in common use for supporting the shafts of horizontal water-wheels.

The case B, surrounding the wheel, has through its vertical sides the passages E E, by which water is admitted to the wheel F, turning in the direction indicated by the arrow.

The gates 1 2 3 are hung within the passages, and against the rear side, (in reference to the revolution of the wheel,) having at the back edge a circular boss, fitting in a circular recess in the wall of the passage, and turning on a rod or bolt passing down through the centre of said boss.

The gate 1 is shown closed, the gate 2 partly open, and 3 still wider open. A boss is also formed at the front edge of the gate, on the outside, into which a vertical rod may be inserted, for regulating the movements and position of the gate. Said rod passing up through a slot in the cover of the case, and being connected by the strap G to the circular plate H on the top of the cover. The plate H is riveted to the plate I, and this again to the lever J, both the plates and lever turning on the shaft A. The outer end of the lever J may be moved by a crank, with rack and pinion, or by other suitable device, and by its motion the gates will be drawn open or closed, according to the direction in which it is moved, and thus the width of the opening may be regulated, and the water cut off at the most advantageous point, under the circumstances of each particular case. As the gate is opened, the pressure of the head of water without will force a vertical sheet, wider or narrower, according to the width of the opening, directly along the straight wall or guide K to the circumference of the wheel at L, striking it about in the direction of a tangent to the circumference at that point, and extending inward from the circumference only according to the width of the sheet.

By this arrangement the water is applied at the most advantageous point, and in the most advantageous direction, without losing any of its force by having its direction changed after passing the point at which the full force of the head of water acts, for if its direction be in any way changed, after passing that point, by gates or guides, a portion of its force is, in accordance with a well-known mechanical principle, necessarily lost.

In constructing my double-rim wheel, I support the upper rim, N, fig. 2, by the top F and the conical brace O, or by arms in place of the conical brace, and contract its diameter from the top downward, according to the width of the bucket P, to be placed upon it, and extend it downward somewhat below the top of the lower rim R. Then making the lower part of the bucket of such width that it will just reach from the inner or upper rim to the outer or lower one, and joining one edge to one rim, and the other to the other rim, where it passes down obliquely, and nearly horizontally between them, I thus connect the lower rim to the upper, and support it.

The diameter of the lower rim is contracted from the top downward, so as to make a space between the case and the rim, for a bucket of about half the width of those on the upper rim.

By this arrangement the water from both sets or series of buckets is discharged downward from the tail of the bucket, that from the upper series passing down between the two rims, and that from the lower series passing down in like manner between the rim and the case.

The foregoing being a description of my improvements in water-wheels, what I claim, and desire to secure by Letters Patent, is—

The above-described water-wheel, having an upper and lower rim, and two sets of buckets, arranged in relation to each other substantially as described.

WILLIAM KENNEDY.
